CLAIM

The ornamental design for a paint can attachment, as shown and described.

DESCRIPTION

FIG. 1 is a top plan view of a paint can attachment showing my new design;

FIG. 2 is a bottom plan view;

FIG. 3 is a side elevational view; and

FIG. 4 is an enlarged, fragmentary cross-sectional view taken on line 4—4 of FIG. 1.

FIG. 1.FIG. 2.FIG. 3.FIG. 4.
